DESIGN FOR A COLLAR HOLDER

Joseph Shaulson, Providence, R. I.

Application April 10, 1941, Serial No. 100,287

Term of patent 7 years

To all whom it may concern:

Be it known that I, Joseph Shaulson, a citizen of the United States, residing at 96 Colonial Road, Providence, in the county of Providence and State of Rhode Island, have invented a new, original, and ornamental Design for a Collar Holder, of which the following is a specification, reference being had to the accompanying drawing forming a part thereof.

Fig. 1 is a side elevation of a collar holder showing my new design; and

Fig. 2 is a top plan view thereof.

I claim:

The ornamental design for a collar holder, substantially as shown.

JOSEPH SHAULSON.
